UNITED STATES PATENT OFFICE.

IRA A. WEAVER, OF SPRINGFIELD, ILLINOIS, ASSIGNOR TO SATTLEY MANUFACTURING COMPANY, OF SPRINGFIELD, ILLINOIS, A CORPORATION OF ILLINOIS.

CULTIVATOR.

SPECIFICATION forming part of Letters Patent No. 738,265, dated September 8, 1903.

Application filed May 11, 1903. Serial No. 156,683. (No model.)

To all whom it may concern:

Be it known that I, IRA A. WEAVER, a citizen of the United States, residing at Springfield, Sangamon county, State of Illinois, have **5** invented certain new and useful Improvements in Cultivators, of which the following is a specification containing a full, clear, and exact description, reference being had to the accompanying drawings, forming a part **10** hereof.

My invention relates to improvements in cultivators; and it consists of the novel construction, combination, and arrangement of parts hereinafter shown, described, and **15** claimed.

The object of my invention is to provide an improved coupling by means of which the beams may be quickly and easily attached to the frame of the cultivator.

20 A further object is to provide improved means for taking up all of the lost motion in the coupling.

A further object is to provide improved means for raising and lowering the beams **25** and at the same time permit the beams to have an easy lateral motion.

In the drawings, Figure 1 is a side elevation of a portion of a straddle-row cultivator having my invention applied thereto. Fig. **30** 2 is a detail view in perspective of the adjustable coupling. Fig. 3 is a detail view in perspective of a key made use of in securing the pivot-head to the arch-sleeve. Fig. 4 is a detail view in perspective of the adjustable **35** bar and its clamp for the upper journal of the beam-head, inverted for the purpose of better illustration. Fig. 5 is a sectional detail view of the lower pivot-head journal and its bearing in the beam-head on line 5 5 of Fig. 2.

1 indicates the usual supporting-wheels, which have been broken away at convenient points to illustrate more important parts.

2 indicates the cultivator-beams, upon the **45** front end of which are secured, by means of bolts 3, beam-heads 4, which have vertically-alined bearings 5 and 6, separated a distance. The upper bearing 5 preferably has a conical bore to fit the conical upper pivot 7 of the **50** pivot-head 8. Said upper bearing 5 is both adjustably and detachably mounted between

the split jaws 9 and 10 of the beam-head, and said bearing is clamped between said jaws by means of a bolt 11. The upper end of said bearing 5 projects a distance and is provided with an angular portion 12 for the reception of a wrench. The under surfaces of the jaws 9 and 10 are provided with spiral projections 13, which are engaged by integral lugs 14, projecting laterally from the lower **55** end of said bearing 5 for a purpose hereinafter mentioned. The lower pivot 15 of the pivot-head 8 is conical and fits within its conical lower bearing 6. It will thus be seen that the beam-heads are pivotally and **60** adjustably connected to their respective pivot-heads 8. I have shown only one of each part, except the cultivator-shovels and beams, as I have deemed it unnecessary to duplicate the beam-heads, pivot-heads, and their operating connections.

The pivot-head 8 is adjustably secured upon the arch-sleeve 16 by means of a tapered key or wedge 17, mounted in the key-seat 18 and secured by the nut 19, threaded **75** upon the lower end of said key. Said arch-sleeve is journaled on the horizontal lower end 20 of the arch 21, which latter is secured to the frame 22 of the cultivator in the usual manner.

80 My improved means for raising and lowering the beams consists of a lifting-arm 23, having its forward end pivotally connected to a perforated ear 24, projecting from the side of the beam-head 4 adjacent the upper **85** end of the latter. Said lifting-arm extends rearwardly and is located a short distance above its beam 2. It is provided with an angular brace 25, the upper end of which is secured at 26 to the said lifting-arm, and the lower end of which brace is pivotally connected to a perforated ear 27, projecting from the lower portion of the beam-head 4. However, I do not desire to limit myself to the construction just described, as it is evident that **95** the said arm and its brace may be formed integral, or some other equivalent construction may be provided.

Raising and lowering the beams 2 is accomplished by means of a hand-lever 28, fulcrumed at 29 to the frame and provided with the usual toothed sector 30 for locking said

lever in the desired position. A vertical rod 31 is pivotally connected to the rear end of the lifting-arm 23, and the upper end of said rod 31 is pivotally connected to the hand-lever 28. The connection between the hand-lever 28 and rod 31 is preferably yielding by means of a spring 32 and a sliding connection between said spring and the hand-lever.

The above-described construction may of course be duplicated in order to provide a cultivator of any capacity.

The operation is as follows: When it is desired to raise and lower the beams 2, the hand-lever 28 is manipulated, and said beams 15 may be raised and lowered and at the same time be permitted to have an easy lateral motion on their pivot-heads 8. When it is desired to take up the lost motion between the bearings 5 and 6 of the beam-head and their 20 pivots, all that is necessary is to loosen the bolt 11, thereby releasing the adjustable bearing 5, and then the same should be given a slight axial movement by means of a wrench applied to the angular portion 12, which will 25 cause the lugs 14 to engage the spiral projections 13 on the under side of the jaws 9 and 10, and said spiral projections will force the said bearing 5 downwardly a corresponding distance, thereby bringing it into closer 30 contact with its pivot.

The construction above described possesses a number of readily-apparent advantages in point of convenience and durability.

I claim—

35 1. In a cultivator, the combination with the supporting-arch and the frame, of a pivot-head journaled upon said arch and having upper and lower pivots, a beam, a beam-head mounted upon the pivots of said pivot-head, 40 and an adjustable bearing mounted to rock axially upon said pivot-head for taking up the lost motion between said pivot-head and said beam-head, substantially as described.

2. In a cultivator, the combination with the 45 supporting-arch and the frame, of a pivot-head journaled upon said arch and having upper and lower pivots, a beam, a beam-head mounted upon the pivots of said pivot-head, an adjustable bearing mounted to rock axially upon said pivot-head for taking up the 50 lost motion between said pivot-head and said beam-head, and means for locking said adjustable bearing after the lost motion has been taken up, substantially as described.

55 3. In a cultivator, the combination with the supporting-arch and the frame, of a pivot-head journaled upon said arch and having upper and lower pivots, a beam, a beam-head mounted upon the pivots of said pivot-head, 60 an adjustable bearing for taking up the lost motion between said pivot-head and said

beam-head, and clamping-jaws for securing the said adjustable bearing after the lost motion has been taken up; substantially as described.

4. In a cultivator, the combination with the supporting-arch and the frame, of a pivot-head journaled upon said arch and having upper and lower pivots, a beam, a beam-head mounted upon the pivots of said pivot-head, 70 an adjustable bearing for taking up the lost motion between said pivot-head and said beam-head, said bearing having an angular projection for the reception of a wrench, and a clamp for locking said bearing after the 75 same has been adjusted, substantially as described.

5. In a cultivator, the combination with the supporting-arch and the frame, of a pivot-head journaled upon said arch and having 80 upper and lower conical pivots, a beam, a beam-head mounted upon the conical pivots of said pivot-head, an adjustable conical bearing for taking up the lost motion between said pivot-head and said beam-head, said bearing 85 having an angular projection for the reception of a wrench, and a clamp for locking said bearing after the same has been adjusted, substantially as described.

6. In a cultivator, the combination with the 90 supporting-arch and the frame, of a pivot-head journaled upon said arch and having upper and lower pivots, a beam, a beam-head mounted upon the pivots of said pivot-head, an adjustable bearing for taking up the lost 95 motion between said pivot-head and said beam-head, a lifting-arm pivotally connected to said beam-head and extending rearwardly therefrom, a hand-lever, and a connection between said hand-lever and said lifting-arm, 100 substantially as described.

7. In a cultivator, the combination with the supporting-arch and the frame, of a pivot-head journaled upon said arch and having upper and lower pivots, a beam, a beam-head 105 mounted upon the pivots of said pivot-head, an adjustable bearing for taking up the lost motion between said pivot-head and said beam-head, clamping-jaws between which said adjustable bearing is mounted, a lateral 110 projection on said bearing, and spiral projections on said jaws with which said projection upon said bearing is adapted to contact, substantially as described.

In testimony whereof I have signed my 115 name to this specification in presence of two subscribing witnesses.

IRA A. WEAVER.
